Tire, top left side of page.*Primary Examiner*—James M. Gandy*Attorney, Agent, or Firm*—Marmaduke A. Hobbs[57] **CLAIM**The ornamental design for a tire, substantially as shown
and described.**DESCRIPTION**FIG. 1 is a perspective view of a tire showing my new
design, it being understood that the tread pattern is
repeated throughout the circumference of the tire and
the opposite side being substantially the same as that
shown;

FIG. 2 is a side elevational view thereof;

FIG. 3 is a front elevational view thereof; and

FIG. 4 is a fragmentary cross-sectional view thereof
taken along line 4—4 in FIG. 3.Fig. 1
